SPEED CONTROLLING MEANS FOR
SPINNING MACHINES

William A. Mayor, deceased, late of Niskayuna,
N. Y., by Eva V. Mayor, administratrix, Lynn,
Mass., assignor to General Electric Company, a
corporation of New York

Application May 19, 1934, Serial No. 726,587

5 Claims. (Cl. 118—32)

This invention relates to speed controlling means for ring spinning machines and the like, and has for its object the provision of simple and reliable means for automatically varying the speed to give a desirable high operating efficiency.

5 More particularly, the invention relates to a means for automatically varying the speed of the spindle, as the yarn is wound on the bobbin in such a manner as to maintain a constant tension in the yarn. It will be understood that in filling wind operations, to which this invention relates in particular, the yarn is wound on the bobbin in conical layers. At the beginning of the winding operation, however, a conical base is built up on the lower end of the bobbin, the layers being thereafter conical for the completion of the winding operation. In carrying out this winding operation, the yarn is thus wound on portions of the bobbin of a continually varying diameter. It is an inherent characteristic of ring spinning machines that the tension on the yarn varies inversely with the diameter of the portion of the bobbin on which the thread is being wound, assuming a constant speed for the bobbin. This invention relates to improved means for automatically varying the speed of the spindle directly with the diameter of the bobbin, so as to maintain constant tension in the yarn.

30 In carrying out the invention, linkage mechanism is provided between the speed controlling means for the spinning machine and an element of the machine having an amplitude of oscillating movement proportional to the amplitude of relative movement between the spindle and the ring rail, together with a cam driven in accordance with the progressive relative movement between the ring rail and the spindle as the bobbin is built up. This cam cooperates with the linkage mechanism so as to give a low base or minimum speed at the beginning of the winding operation, and gradually increase this base speed to a maximum base speed after the conical base has been wound.

45 For more complete disclosure of the invention reference should now be had to the drawing, Fig. 1 of which shows speed control means embodying the invention applying to a typical ring spinning machine, while Fig. 2 is a curve showing the speed variations of the machine plotted as ordinates with respect to time plotted as abscissas.

50 Referring to the drawing, the invention is shown in one form as applied to a typical ring spinning machine. For purposes of clarity only 55 the essential elements of the spinning machine

directly cooperating with the speed varying means are shown. In this particular machine, the ring rail is fixed in position, while the spindle is oscillated up and down and progressively moved downward as the winding operation proceeds. Obviously, however, the spindle may be stationary and the ring rail given a corresponding movement.

The spindle (not shown) is oscillated up and down by means of a chain 10 connected thereto and having its other end connected to the end of a shaft 11. This shaft 11 has a threaded portion 12 and it is continually rotated at a predetermined constant speed by a driving connection (not shown) connecting it to the electric motor 13 forming the driving means for the entire machine. The shaft 12 is also provided with a splined connection with its supporting and driving member 14 so that as the shaft rotates, it is moved longitudinally by reason of its threaded connection with a nut 15 secured on the upper end of an oscillating arm 16, the lower end of which is provided with a fixed and adjustable pivot 17. This longitudinal movement of the shaft 12 is toward the left, as viewed in the drawing, as the bobbins are built up and gives the spindles a progressive lowering movement with respect to the ring rail.

The arm 16 is oscillated about its pivot 17 by means of a cam 18 forming a part of the machine and driven from the electric motor 13. The cam bears directly on a roller 19 on the lower end of an arm 20, having a fixed and adjustable pivot 21 at its upper end. This arm 20 bears at an intermediate point on a roller 22 secured to a member 23 which is slidably mounted on a guide (not shown) secured to the arm 16 and extending longitudinally thereof.

Thus it will be observed that as the arm 16 is oscillated about its pivot 17, its upper end moves the shaft 12 back and forth in its splined connection with the driving member 14, whereby the spindle is correspondingly oscillated up and down with respect to the ring rail. The arm 16 is therefore an element oscillating in accordance with the relative oscillatory movement between the ring rail and the spindle.

With the parts in the positions shown, the roller 22 is in its lowermost position, which it occupies during the main portion of the winding operation. At the beginning of the winding operation, the roller 22 is in a raised position as compared to that shown, so as to give a shorter amplitude of movement to the arm 16. As will be understood by those skilled in the art, the

roller 22 is initially raised by temporarily disconnecting the driving connection for the shaft 12 and turning the shaft manually so as to feed it back toward the right as viewed in the drawing through the nut 15, whereby the spindle is raised and the gear 25 on the shaft is brought into engagement with the rack on the member 23. Further continued rotation of the shaft 12 causes the gear 25 to raise the member 23 and with it the roller 22 to an uppermost position.

10 This sets the machine for the beginning of a winding operation. During the initial stages, while the conical base is being formed, the gear 25 gradually moves the member 23 downward 15 until, when the conical base has been formed, the member 23 has arrived at its lowermost position shown, in which the gear 25 no longer engages it. It will further be understood that the gear 25 is provided with a projection (not shown) 20 on its periphery, which cooperates with a recess in the upper end of the rack so as to assure proper engagement of the gear with the rack when the spinning machine is reset.

25 It will be understood that the mechanism so far described is old in the art, and is shown as typical of ring spinning machines for the purpose of a clearer understanding of the invention. Obviously, however, the invention is applicable to 30 spinning machines having structures different from that shown.

35 While any suitable variable speed driving motor 13 may be used in accordance with the invention, a three-phase, slip-ring induction motor is shown. The speed of this motor is controlled by 40 means of a rheostat 26 shown as having three resistances, 27, 28 and 29 connected respectively in the rotor circuits of the motor, and being variable by means of a rotatable contact device 30 having three arms cooperating respectively 45 with the resistances.

45 The rheostat 26 is operated automatically through suitable linkage mechanism by the joint operation of the cam 18 and a second cam 31. The connection with the cam 18 is made through 50 the arm 16. As shown, the contact device 30 is rotated by a rack 32 having its end pivotally connected at the point 33 with the upper end of a link 34. The lower end of the link 34 is pivotally 55 connected at the point 35 with the lower end of an arm 36 having a fixed pivot 37 at its upper end. A connection is made between the link 34 and the arm 16 by means of a link 38 joining intermediate points of these two members. It 60 will therefore be observed that as the arm 16 oscillates, it imparts an oscillatory movement of proportionate amplitude to the link 34 about its pivot 35. This accordingly moves the contact device 30 back and forth, so as to correspondingly increase and decrease the speed of the 65 motor.

65 This control of the speed from the cam 18 is modified by the action of the cam 31 which bears on a roller 40 secured to an intermediate point of the arm 36. The cam 31 is driven 70 through a suitable worm and worm wheel gear 41 from a sprocket wheel 42 which is connected through a chain 43 to the driving element 14 of the shaft 12. Although the driving element 14 makes many revolutions during each winding operation, the driving connection with the cam 31 has such a high ratio that the cam makes somewhat less than one complete revolution during the winding operation. The function of the

cam 31 is to gradually increase the base operating speed of the machine as the conical base is being wound on the bobbin. It is provided with a single operating projection 45 which, at the beginning 5 of a winding operation is in a position displaced one-half revolution from that shown in the drawing, so that its point is in engagement with the roller 40. In this position of the cam 31 it will be observed that the arm 36 is displaced somewhat from the position shown in 10 the drawing in a counter-clockwise direction about the pivot 37. This displaces the pivot 35 of the link 34 in the same direction thus swinging the link 34 about its pivotal connection 46 with the link 38 as a pivot and moving the rack 15 32 farther toward the left, whereby the rheostat arm 30 is moved to a position to include the entire amounts of the resistances 27, 28 and 29 in 20 the motor circuits and give the lowest speed of the driving motor.

Assuming now that the shaft 12 has been reset for the beginning of a winding operation with the roller 22 at the upper limit of its movement in the operation of the machine the motor speed is 25 successively increased and decreased by the rotation of the cam 18. These amplitudes of speed variation gradually increase as the roller 22 is moved downward. At the same time, the cam 31 turns slowly to increase the minimum or base speed. This is shown graphically in Fig. 2. The portion of the curve between the points 47 and 48 corresponds with the building up of the conical base, and it is over this portion that the projection 45 on cam 31 functions to gradually increase the base speed from an initial low value of for example 5300 R. P. M. Thereafter, the roller 40 is in engagement with the circular concentric portion of the cam, and consequently the base speed remains unchanged and at its maximum during the completion of the winding operation, 40 the motor speed then being controlled solely by the cam 18 through a definite fixed amplitude. The period between the points 47 and 48 (Fig. 2) may represent about 40 minutes, whereas the main winding operation with maximum base 45 speed represented by the remaining portion of the curve may extend over a period of seven or eight hours.

With the various parts in the positions shown in the drawing the spindle occupies its lowermost 50 position and the machine as indicated by the position of the cam 31 is carrying out the main winding operation with fixed highest base speed at which it is operating. This highest base speed may for example be 6300 R. P. M., with a maximum speed of 7000 R. P. M.

55 It will be observed that the portion of the curve 47-48 indicates gradually increasing amplitudes of the successive speed variations. This is due to the fact that at the beginning of 60 the winding operation the member 23 and hence the roller 22 carried by it is in its uppermost position and consequently the cam 18 is effective to give only a relatively short oscillatory movement to the arm 16. As the roller 22 is moved downward this oscillatory movement of the arm 16 increases with increasing amplitude of speed variation up to the final position shown in the drawing.

70 It will be understood that when the machine is reset manually, as previously described, the cam 31 is thereby turned back to its initial position with the point of the projection 45 in engagement with the roller 40.

What is claimed as new and desired to secure by Letters Patent of the United States, is:—

1. Apparatus for varying the speed of a ring spinning machine or the like, comprising means for varying the speed of the machine, an operating connection between said speed varying means and an element of the machine oscillating in accordance with the relative oscillatory movement between the ring rail and the spindle whereby said speed varying means is oscillated to give a desired amplitude of machine speed variation above a predetermined base speed, and cam means driven in accordance with the progressive relative movement between the ring rail and the spindle for operating said speed varying means independently of said element so as to increase the base speed of the machine independently of the amplitude of speed variation of the machine during the winding of a predetermined portion of the bobbin after which said cam means maintains a substantially uniform base speed.

2. Apparatus for varying the speed of a ring spinning machine or the like, comprising means for varying the speed of the machine, an operating arm therefor, a mechanical connection between said arm and an element of the machine oscillating in accordance with the relative oscillatory movement between the ring rail and the spindle whereby said speed varying means is oscillated to give a desired amplitude of machine speed variation above a predetermined base speed, cam means driven in accordance with the progressive relative movement between the ring rail and the spindle, and an operating connection between said cam means and said arm, said cam means being provided with an operating portion for moving said arm independently of said element to increase the base speed of the machine independently of the amplitude of speed variation of the machine during the winding of the base of the bobbin, after which said cam means maintains a substantially uniform base speed.

3. Apparatus for varying the speed of a ring spinning machine or the like provided with an oscillating member having a movement corresponding with the relative oscillating movement between the ring rail and the spindle, a speed control device, a link connected to operate said speed control device, a movable pivot for said link, a connection between said link and the oscillating member whereby said link is oscillated about said pivot to operate said speed varying means, a cam arranged to move said pivot, and means for driving said cam in accordance with the progressive relative movement between the ring rail and the

spindle, said cam having a relatively short operating portion for moving said pivot to gradually increase the base speed of the machine during the winding of the base of the cop, after which said cam maintains a substantially uniform base speed during the main winding operation.

4. Apparatus for varying the speed of a ring spinning machine or the like provided with an oscillating member having a movement corresponding with the relative oscillatory movement between the ring rail and the spindle, a speed control device, an arm, a link connected at one end to said speed control device, a pivotal connection between said link and said arm, a second link forming a connection between the oscillating member and said first link, whereby said first link is oscillated about said pivotal connection on said arm and thereby operates said speed varying means, a cam cooperating with said arm so as to move said pivotal connection, and means for driving said cam in accordance with the progressive relative movement between the ring rail and the spindle, said cam having a relatively short operating portion for gradually increasing the base speed of the machine during the winding of the base of the cop, after which said cam maintains a substantially uniform base speed during the main winding.

5. Apparatus for varying the speed of a ring spinning machine or the like provided with an oscillating member having a movement corresponding with the relative oscillatory movement between the ring rail and the spindle, a speed control device, an arm, a link having one end connected to said speed control device, and its other end pivotally mounted on the free end of said arm, a second link connecting an intermediate point of said first link to the oscillating member of the spinning machine, whereby said first link is oscillated about its pivotal connection on said arm, a cam cooperating with an intermediate point of said arm, and means for driving said cam in accordance with the progressive relative movement between the ring rail and the spindle as the cop is wound on the spindle, said cam having an operating projection engaging said arm at the beginning of the winding of the cop so as to move the pivot of said first link and thereby operate said speed control means to progressively increase the base speed of the machine for a predetermined period, after which said cam maintains a substantially uniform base speed.
